TELEVISION PICKUP CONTROL SYSTEM

George L. Beers, Haddonfield, N. J., assignor to
 Radio Corporation of America, a corporation of
 Delaware

Application April 25, 1944, Serial No. 532,579

16 Claims. (Cl. 178—7.2)

1

This invention relates to automatic control apparatus, and more particularly to control apparatus in which a control function is exercised in accordance with a selected series of values from which a control actuating value may be derived.

The invention is illustrated as being applied to a novel arrangement for obtaining automatic focusing of a television camera. Automatic focusing systems, in order to be fully effective, must insure against the possibility of accidental focusing on an unimportant portion of the field of view, and moreover, it is desirable to provide for selecting the portion of the field of view which, in the opinion of a skilled operator, is the important portion, or the center of interest of the field of view when it is considered as an artistic composition. The present invention has for its principal aim not only to prevent inadvertent focusing on unimportant portions or objects of the field of view, but to provide a positive means whereby a definite object or a desired portion of the field of view will be automatically kept in focus and may be selected at will.

Another important object of the present invention is to provide a control system operable in response to a selectable control value.

A further object of the present invention is to provide means in a control system for selecting a source of control values.

Still another object of the invention is to provide a novel motor control system for a reversing motor which will automatically insure operation in a desired direction.

Still another object of the invention is to provide a novel arrangement for deriving a control signal.

A still further object of the present invention is to provide novel means in a television pickup system for selecting the portion of the field of view from which a control signal or series of signals are to be derived.

Still further objects of the invention will become apparent and suggest themselves to those skilled in the art to which the invention is directed upon reading the following specification and claims in connection with the drawings in which:

Fig. 1 is a schematic showing of a television pickup system, including a television camera and a portion of the focusing equipment of the present invention;

Figs. 2 and 3 illustrate additional equipment which is associated with the focusing equipment of Fig. 1; and

Fig. 4 shows a slight modification of Figs. 1 and 2.

2

The television pickup system selected for purposes of illustration is more or less conventional and comprises a camera 9 (suggested in dotted outline) housing a pickup tube 10 shown as being of the storage type containing a light sensitive mosaic 11 and the usual auxiliary electrodes and electron emitters. These electrodes include the anode and the cathode for producing a cathode ray beam. The cathode ray beam deflecting means or yoke is indicated conventionally at 12 and may comprise horizontal and vertical deflecting coils for producing a scanning movement of the beam 14 which is directed onto the mosaic 11 to release a signal output therefrom to a load circuit. The released signal output of the pickup tube 10 is applied to a preamplifier 15 across a load resistor 16 in most conventional devices. After initial amplification and, if desirable or necessary, additional amplification, the signal is transmitted to a line amplifier 17. Reference numeral 18 indicates a sync signal generator of conventional form which generates suitable synchronizing and blanking signals, in known manner, and which is shown as being connected to the ray deflecting means 12 by way of conductors 25 and 26 to supply the horizontal and vertical beam deflection energy. A conductor 29 connected to the control electrode 31 of the electron gun 32 of the scanning tube 10 provides the return line blanking. The same general types of signals are also applied to the line amplifier 17 by way of conductors 34. The resulting composite sync and picture signal output of the amplifier 17 may be transmitted over any suitable transmission channel as 35 to a distribution point such as a radio transmitter.

The camera 9 is equipped in the usual manner with a lens combination 36 suitable for imaging the scene, indicated conventionally at 38, on the mosaic 11. The lens combination 36 is or may be equipped with the usual iris diaphragm (not shown) for stopping down the lens to obtain greater depth of focus when the televised scene is well illuminated. A view finder lens combination 41 projects an image of the scene 38 through an inclined, half silvered mirror 42 onto a ground glass view finder screen 44. It will be understood that the scene 38 possesses three dimensions. Any known means may be used for parallax correction between the lens systems. The purpose of the mirror 42 together with an associated cathode ray tube 43 will be described in detail herein-after.

A rack 46 and pinion 47 connected to the support for the lens combinations 36 and 41 pro-

vide means for focusing the camera upon rotation of the pinion 47 by a focusing motor 49. Energization of the motor 49 is obtained under control of a derived signal in accordance with the invention in a manner to be later described.

Referring now to the equipment for generating a control signal and for the present more specifically to Fig. 2, conductor 51 furnishes horizontal sync pulses for control of a sine wave oscillator 52 which runs at image line frequency. A phase shifter 53 of any known type is adjustable to shift the phase of the output of the oscillator 52. A phase shift range of approximately 180° is desirable. One cycle of the output from the oscillator 52 is shown conventionally above the oscillator and the phase shifter. An amplifier 54 amplifies successive half cycles of the wave which are passed through a clipper stage 56. The clipped half wave, indicated at 58, is passed through a shaper and amplifier 61 which gives the half wave approximately the form shown at 62.

Vertical sync pulses from the sync signal generator 18 are applied over a conductor 64 to a sine wave oscillator 66. The output from this oscillator is passed to a phase shifter 67, and the equipment following this phase shifter comprising an amplifier 68, a clipper stage 69, and a shaper and amplifier 71 corresponds in function to the equipment following the phase shifter 53. A pulse 72, similar to the pulse 62, appears in the output of the wave shaper and amplifier 71 but occurs in timed relationship with respect to the vertical sync pulses supplied from the sync generator. A phase shift range of approximately 180° for the output of the oscillator 66 is also desirable.

The pulses 62 and 72 are combined in a conductor 74 including a coupling condenser 75 to provide an operating bias for the grid 70 of the cathode ray tube 43, and also an operating bias for a spot selector amplifier 76 which amplifies the image signal output of the preamplifier 15. The operating biases of both the cathode ray tube 43 and the amplifier 76 are adjusted so that the combined voltage of the pulses 62 and 72 causes these pieces of equipment to become operative when the pulses coincide in time.

The luminous spot generated in the fluorescent screen 77 of the cathode ray tube 43 by the cathode ray beam 78 is thereby shiftable over the face of the tube and is reflected from the half silvered mirror 42 onto the ground glass viewing screen 44. It is preferred that light from the luminous spot is of low intensity so that it does not obliterate any part of the image of the scene 38. It will be understood that the elements of the tube 43 are provided with the usual operating and biasing voltage connections (not shown).

The luminous spot produced by the beam 78 may be shifted to substantially any point on the screen 44 by manipulating the phase shifters 53 and 67, and when this is done the spot selector amplifier 76 passes the portion of the image signal from the preamplifier 15 representing only this luminous spot. In this manner an identifiable portion of the picture signal appearing in the output of the spot selector amplifier 76 may be selected by manipulating the two phase shifters shown on Fig. 2 of the drawings. The selected identifiable portion of the three dimensional scene 38 may lie at any point in its depth.

The motor 49 is operated so as to focus the lens 36 on this selected portion of the scene 38 by comparing the high frequency response from the

camera tube 10 representative of the chosen area during one interval of time to the high frequency response during the next succeeding interval of time. The control circuits to be described for the motor 49 are so arranged that if the motor is moving the lens in a given direction to bring it in focus on the desired area, the high frequency response in the second time interval will be greater than during the first time interval. Under this condition, the control circuits are so arranged that the motor continues to move the lens in the same direction. When the high frequency response during the second interval of time is less than during the first interval, the control circuit will operate to reverse the motor.

The control signal which is applied to a relay 82 to determine direction of rotation of the motor is derived by the apparatus of Fig. 3 of the drawings. The higher frequency components of the selected portion of the image signal are passed by a high pass filter 84 (Fig. 1), and this high frequency signal is applied to the control electrodes 86 and 87 of vacuum tubes 88 and 89 over a conductor 90.

In order to set the time intervals of the successive high frequency response signals, an oscillator 92 is provided which may operate at any desired frequency. This frequency may be determined for example by the time required for the focusing motor to move the lens by an amount which is sufficient to produce a desired change in the high frequency output of amplifier 76 and filter 84. If a time interval of high frequency response comparison is to be $\frac{1}{10}$ of a second, for example, the oscillator 92 may be a 10 cycle oscillator. The output 94 of the oscillator 92, which, if desired, may be of the sine wave form, is changed to square wave form 96 in a wave shaper 98. The waves 94 and 96 are, it will be understood, not shown to scale along the time axis with respect to the wave 58, for example, which may be several thousand pulses per second.

The square wave output from the wave shaper 98 is applied to amplifiers 101 and 102. The voltage output wave of the amplifier 101 is applied to the grid 86 of tube 88, and the output voltage of amplifier 102 is applied to the grid 87 of tube 89. The voltage wave 106 may be considered as shifted in phase by 180° from the voltage wave 107 or may be considered as of reverse polarity. The tubes 88 and 89 are so biased that they function to amplify the signals applied to their grids over the conductor 90 during one half of each voltage wave. In this way tube 88 is caused to function during a desired series of spaced time intervals. Tube 89 is, however, caused to function on the alternate time intervals so that tubes 88 and 89 are functioning on equal and alternate time intervals. The difference in phase between voltage waves 106 and 107 can be obtained by the use of an additional stage of amplification in either amplifier 101 or 102. Coupling condensers 108 and 109 supply high frequency response signals from the high pass filter 84 to the grids 86 and 87 of tubes 88 and 89 respectively.

A network, comprising a pair of rectifier tubes 112 and 114 supplied from the cyclically operating amplifier tubes 88 and 89, serves to rectify the high frequency signals applied to the rectifiers across resistors 115 and 116. The high frequency signals across resistor 115 are applied to rectifier 114. The rectification of these signals by the tube 114 causes terminal 120 of resistor 115 to become more negative with respect to terminal 116. Likewise the high frequency signals applied

to rectifier 112 across resistor 113 causes terminal 117 to become more negative with respect to terminal 116. Thus, it will be seen that the potential between terminals 120 and 117 may be either positive or negative depending on the relative strength of the high frequency signals applied to rectifiers 112 and 114.

A resistor 118 and a condenser 119 serve to average the successive pulses rectified by the rectifiers 112 and 114 so as to obtain an averaging effect. Thus, the terminal 110 likewise becomes either positive or negative with respect to terminal 117 as the relative strength of the high frequency signals applied to rectifiers 112 and 114 is varied.

The polarity changes appearing at the point 110 are applied over a conductor 19 to the relay 82. This relay is a polar relay so constructed that its contact tongue or tongues remain in the position assumed prior to de-energization. Reversal of the position of its contact tongue or tongues requires a change in direction in the current passing through the relay operating coil.

The motor 49 is energized from a suitable source such as the direct current source 121, either the motor armature or the motor field 122, in this instance the motor armature, being connected across the source 121. A line switch (not shown) may be employed to disconnect the motor and relays when the apparatus is idle. To provide for reversing the direction of rotation of the motor, the field 122 is connected to the source 121 through the tongues and contacts of the polar relay 82 and the tongues and contacts of another polar relay 124. The relay 124 is also of the type which requires a reversal in the direction of the current applied to its operating coil before the position of its contact tongues is reversed.

These relays are connected as shown so as to serve as reversing switches for the motor 49. A make contact 126 and a break contact 128 of the relay 82 are connected to one conductor, and a make contact 129 and a break contact 131 are connected to the other line conductor. The conductors 133 and 134 are connected to the motor field 122 through contact tongues 136 and 137 of the relay 124, the stationary contacts of which are wired in the manner explained in connection with the stationary contacts of the relay 82. Reversal of the position of the tongues of either relay will cause the motor 49 to reverse its direction of rotation. If, however, the position of the tongues of both relays is reversed, then the motor will continue to operate in the same direction as will be obvious from an inspection of Fig. 1 of the drawings. While relays have been shown, illustratively, to accomplish this purpose, it will be understood that other means may be employed.

To insure operation of the focusing control of the invention so that the camera will be brought into focus upon starting the system, normally closed limit switches 141 and 142 are provided which cooperate mechanically with suitable means such as the projections 143 and 144 on a movable part of the support 46 for the lens combinations 36 and 41. These limit switches are connected across the source 121 in series with the operating coil of a relay 147 and are opened upon over travel of the lens support 46. The break contact 148 of the relay 147 energizes the operating coil of a stepping magnet 149 when either of the limit switches 141 or 142 is opened. The stepping magnet is provided with a pawl 151 cooperating with a ratchet 152 which intermittently drives the

switch arm 153 of a rotary switch 154. The switch arm is connected to one terminal of the operating coil of the polar relay 124. Alternate contact studs 156 over which the switch arm 153 is stepped are connected to a suitable power source of negative polarity indicated at 157. The contact studs 159 are connected to a suitable power source of positive polarity indicated by reference character 161. The rotary switch 154 together with its stepping magnet 149 may be of any well known construction, such as the usual telephone minor switch.

From the foregoing it will be obvious that upon each over travel of the support 46, for example toward the left, as viewed in Fig. 1, switch 142 will be opened resulting in de-energization of the relay 147. When this occurs, the stepping magnet 149 is energized to step the switch arm 153 to the next successive contact stud, or as shown in Fig. 1 by way of illustration, onto a contact stud 156 connected to the negative source 157. The position of the contact tongues 136 and 137 with the polar relay 124 will be reversed to reverse the direction of rotation of the motor 49. After the motor has operated in a reverse direction for a period of time, the switch 142 will be reclosed resulting in de-energization of the relay 147 and release of the pawl 151 which will be returned to its initial position by a spring 163. The motor 49 will continue to operate until the lens combination 36 brings the image of the scene 38 substantially into focus on the light sensitive surface of the mosaic 11 of the cathode ray tube 10.

While control relays and polar relays employed as reversing switches have been shown, illustratively, it will be understood that electronic switching means, operating in response to the signals at the terminal 110 to control the motor, may be employed.

All of the equipment involved in this system except the motor 49, the cathode ray tube 43, and the controls for the phase shifters 53 and 61 which move the pattern on the oscilloscope tube 43, may be located at a monitoring control station at a point more or less remote from the camera 9. If so desired, the control for selecting the desired area may be operated by observing the image on a monitoring image tube (not shown) at a supervisory control point. The motor for driving the pinion 47 will usually be located in the camera housing and the control relay equipment may be separately mounted and housed. It will be understood that parts of the equipment located near the camera 9 will preferably be shielded so as to prevent interference with the television signal generating equipment.

In operation of the automatic control system of the invention for focusing the television camera 9 on a particular portion of a field of view or scene 38, the camera man operating the camera 9 would manipulate the control of each phase shifter 53 and 61 until light from the luminous spot produced by the cathode ray beam 78 is superimposed on the portion of the image appearing in the ground glass screen 44 on which the camera is to focus. If the equipment is already in operation, the camera will, before the shift of the luminous spot occurs, have been focused on some portion of the scene 38. However, in the event that the equipment has just been placed in operation, the camera may be quickly brought to focus if the camera man observes that the lens 36 is moving in a direction away from its position of focus by momentarily depressing a key 163 which will cause the direction of movement

of the lens to be reversed immediately. This is accomplished by energization of the operating coil of the stepping magnet 149 to change the polarity of current flowing through the winding of the polar relay 124.

With the area of the scene upon which the camera is to focus selected, as stated previously the high frequency response representative of this area during one interval of time is compared to the high frequency response during a succeeding interval of time. This is accomplished by the biases applied to the grids 86 and 87 of the tubes 88 and 89 respectively from the oscillator 92. The time interval is preferably such that the lens can move between half cycles of the wave from this oscillator. If it is assumed that the motor 49 is moving the lens 36 in the direction to bring it in focus on the desired area, the high frequency response during the second interval will be greater than during the first interval of time. Under this condition the polarity at the point 110 is unchanged, and the motor 49 continues to rotate to move the lens 36 in the same direction.

If the high frequency response during a succeeding interval of time is less than during a preceding interval, the polarity at the point 110 will reverse causing the polar relay 82 to reverse the motor. By this arrangement, the lens 36 will move back and forth through a very narrow range centered about the position of optimum focus. This variation in lens position will not be observable by the television audience since the loss of high frequency response which it produces may be very small, for example, less than 10 per cent, and the camera, pickup tube, and amplifier system can be designed with materially greater resolution capabilities than will be obtained from the complete television system including the receiver. It is doubtful that a skilled camera man could focus a television camera with this degree of accuracy merely by observing the image of the scene 38 in the ground glass view finder 44.

In the foregoing example it was assumed that the initial relationship between the high frequency signals applied to amplifier tubes 88 and 89 and the motion of the lens was such that either the lens moved in the direction to bring the desired scene in focus or that the camera operator used the switch 163 to cause the lens to move in the desired direction. Assuming now that when the initial relationship between the high frequency signals applied to the amplifier tubes 88 and 89 and the motion of the lens is such that the lens moves away from the "in focus" position, the camera operator does not resort to the use of the switch 163. In this case the lens will move to the end of its travel and either the reversing switch 141 or 142 will be operated to reverse the direction of lens motion. The relationship between the high frequency signals applied to the tubes 88 and 89 and the lens motion will then be such as to bring the lens "in focus" on the desired scene.

Fig. 4 of the drawings indicates a modification of the apparatus of Figs. 1 and 2 enabling use of the oscilloscope 43 in conjunction with any usual manual focus control to focus the camera on a selected area of the field of view 38 without observing fine detail in the image projected on the finder screen 44.

The high pass filter 84 is the same as that shown on Fig. 1 of the drawings. When lens 36 is to be moved manually in accordance with the mode of operation now to be set forth, the con-

nexion to the tubes 88 and 89 may be omitted, as well as the driving motor and the motor control apparatus. However, it will be understood that the modified arrangement of Fig. 4 shows a system including the spot selecting equipment in addition to the usual studio and console equipment.

A rectifier 180 rectifies the high frequency output representing the picture area selected in the manner described above by operating the phase shifters 53 and 67. The output of the rectifier appearing across the load resistor 181 is applied to the grid 70 of the oscilloscope 43 so that the spot produced by the beam 78 is brightest when the lens 36 is in focus on the selected spot. Combining the area indicator on the finder screen with the feature of changing the brightness of the spot serving as the area indicator shows the camera operator that the particular spot selected is in focus while he is observing the entire scene included by the camera.

As an alternative a meter 183 either at the camera or at a remote point may be used to indicate when the camera is in focus on the selected area.

As the sensitivity of television pickup tubes is increased, it becomes possible to pick up television images at light levels which are insufficient to provide in a conventional view finder an image which is of sufficient brightness to enable the camera operator to focus the camera on the desired scene by observing the resolution in the visual image. Under these conditions the arrangement illustrated in Fig. 4 is particularly effective since the variation in brightness of the focus indicating spot or the meter indication depends entirely on the signals derived from the pickup tube. Any increase in the sensitivity of pickup tubes therefore automatically provides a corresponding increase in sensitivity of the focus indicating spot.

Various alterations and modifications may be made in the present invention without departing from the spirit and scope thereof, and it is desired that any and all such modifications be considered within the purview of the present invention as defined by the hereinafter appended claims.

Having now described the invention, what is claimed and desired to be secured by Letters Patent is the following:

1. In a television system, means for focusing a scene upon a light responsive area, means for focusing the scene on a viewing area, means for selecting a desired portion of the image of said scene appearing on the viewing area, and means for causing said focusing means to automatically bring the desired portion of said scene in focus.
2. In a television system, means for focusing a scene upon a light responsive area, means for focusing the scene on a viewing area, means for selecting a desired portion of the image of said scene appearing on the viewing area, means for producing signals indicative of said desired portion of said scene, and means for utilizing said signals to vary said focusing means.
3. In a television system, means for focusing a scene upon a light responsive area, means for selecting a desired portion of said scene, means for producing electrical potentials the relative polarities of which are indicative of said desired portion of said scene, and means for utilizing said potentials to vary said focusing means.
4. In a television system, means for focusing a scene upon a light responsive area, means for

obtaining a visual image of said scene to indicate when said scene is in focus on said light responsive area, and means for producing another visual focus indication which can be viewed simultaneously with said visual image.

5. In a television system, means for focusing a scene upon a light responsive area, means for obtaining a visual image of said scene to indicate when said scene is in focus on said light responsive area, and means for producing another visual focus indication superimposed on said visual image.

6. In a television system, means for focusing a scene upon a light responsive area, means for producing a variation in the resolution of a visual image in response to a focusing variation, and additional visual means for producing a manifestation of the displacement of a particular area in the depth of the scene whereby to enable resolution of the particular area on said light responsive area.

7. In a television system, means for focusing a scene on a light responsive area, means for producing a variation in the resolution of a visual image in response to focusing variations, and means for producing an additional indication related to the resolution of the visual image.

8. In a television system, means for focusing a scene on a light responsive area, means for producing a variation in the resolution of a visual image in response to focusing variations, means for producing a cathode ray stream, means for producing a visual indication under control of said stream, and means whereby said last named means is responsive to said focusing means.

9. In a television system, means for focusing a scene on a light responsive area, means for producing a variation in the resolution of a visual image in response to focusing variations, an indicating instrument, and means for producing a change in the indication of said instrument in response to operation of said focusing means.

10. In a television system, means for focusing a scene on a light responsive area, means for producing a variation in the resolution of a visual image in response to focusing variations, means for producing signals representing a portion of said visual image, said signals varying in response to focusing variations, a rectifier for rectifying said signals, and an indicating instrument responsive to the change in current through said rectifier which occurs upon variation of the focus.

11. A control system comprising controlled and controlling elements, means for deriving energy representing the position of the controlled element during a given time interval, means for deriving energy proportional to a successive position during a succeeding time interval, means for comparing the values of the derived energies, means for obtaining a characteristic from said

comparison to which said controlling element is responsive, and means to actuate the controlling element in accordance with said characteristic whereby the derived energy is maintained at a maximum.

12. A control system comprising controlled and controlling elements, means for deriving energy representing the direction of movement of the controlled element during a given time interval, means for deriving energy during a succeeding time interval proportional to continued movement, means for comparing the values of the derived energies, means for obtaining a characteristic from said comparison to which said controlling element is responsive, and means to actuate the controlling element in accordance with said characteristic.

13. In a television system, means for focusing a light image of a subject upon a light responsive area, means for scanning the light responsive area, means for developing electrical energies in accordance with the light intensity of the elemental areas scanned, means for dividing the developed electrical energies into increments separated by time intervals, means for comparing successive increments to determine the difference in frequency components of the successive increments, and means for varying the focusing means in accordance with said comparison means.

14. In a television system, power driven means for focusing a light image of a subject upon a light responsive area, means for scanning the light responsive area, means for developing electrical energies in accordance with the light intensity of the elemental areas scanned, means for dividing the developed electrical energies into increments separated by time intervals, means for comparing successive increments to determine occurrence of a change in frequency components of successive groups of increments, means for producing a characteristic signal upon occurrence of a change in frequency components of successive groups, and means for varying the focusing means in accordance with said characteristic signal.

15. In a television system, means for focusing a scene upon a light responsive area, means for producing electrical effects, characteristics of which are indicative of said scene, and means for automatically causing said characteristics to vary in a desired relationship in response to the actuation of said focusing means.

16. In a television system, means for focusing a scene upon a light responsive area, means for producing electrical potentials the relative polarities of which are indicative of said scene, and means for automatically causing the polarity of said potentials to vary in a desired relationship in response to the actuation of said focusing means.

GEORGE L. BEERS.
